UNITED STATES PATENT OFFICE

2,157,271

CONCRETE WALL STRUCTURE

Emil E. Schmeller, Chewelah, Wash.

Application July 23, 1937, Serial No. 155,234

2 Claims. (Cl. 72—44)

My present invention relates to an improved concrete wall structure of the metal-reinforced, monolithic, and hollow type which is adapted for use in small building structures, as garages 5 and other one-room and one-story building where the walls of the building are each composed of a single concrete slab and the adjoining ends of the slabs or wall-sections are bonded together by concrete. The invention is also capable of embodiment in horizontally aligned wall-sections bonded together and vertically aligned wall-sections that are bonded together to form a complete wall of one, two, or more stories high according to the height of the building, and the usual window and door openings are provided where required.

In carrying out my invention I preferably fashion the wall section by superimposing successive concrete slabs within a horizontally disposed mold-box, and after the plastic material has set the integral wall section is turned on edge to upright position for erection either as a monolithic wall, or a number of sections are aligned and bonded together to form the building wall, 25 and these building walls, usually at the corners, are bonded together by concrete.

In the utilization of my invention I am enabled to manufacture a comparatively light but strong and durable wall section at low cost for labor and 30 material, and the completed wall sections may readily be in building walls that are properly sustained and supported to insure permanence.

The wall sections of my invention may be provided with interior heat-insulating cores, or the 35 interior cellular structures of the walls or wall-sections may be left in hollow condition as desired.

The invention consists in certain novel combinations and arrangements of parts as will hereinafter be more fully set forth and claimed. In the accompanying drawings I have illustrated one complete example of the physical embodiment of my invention wherein the parts are combined and arranged according to one mode I have thus 45 far devised for the practical application of the principles of my invention.

Figure 1 is a view in side elevation of a monolithic wall-section constructed according to my invention, showing a window opening, and partly 50 broken away for convenience of illustration.

Figure 2 is a top edge view of the wall section of Figure 1.

Figure 3 is a horizontal sectional view of the wall-section of Figure 1, showing the window 55 opening therein.

Figure 4 is a transverse vertical sectional view at line 4—4 of Figure 2; and Figure 5 is a similar sectional view at line 5—5 of Figure 2.

Figure 6 is a transverse vertical sectional view at the base of the wall section, showing also the 5 concrete foundation or footing for supporting the wall-section.

Figure 7 is a horizontal-vertical sectional view showing the forms or mold-box in place for bonding together the adjoining edges of wall-sections, 10 and Figure 8 is a sectional view showing the bonds after the forms or mold boxes have been removed.

Figure 9 is a view similar to Figure 8, but showing a solid, upright pilaster as the bond between 15 adjoining edges of two wall-sections.

Figure 10 is a horizontal sectional view at a corner of a building structure, showing the formation of a corner bond between adjoining angularly disposed wall-sections.

Figure 11 is a vertical sectional view through a portion of the horizontally disposed mold or mold-box in which a wall-section has been cast, showing three superimposed slabs forming the integral wall-section, and showing also sand- 25 cores in the interior of the section.

Figure 12 is a detail sectional view of part of the mold or mold box with the plastic material omitted.

Figure 13 is a vertical sectional view through 30 part of a horizontal ceiling or roof structure, showing the manner of supporting the horizontal section on ceiling or roof joists which are supported on the top edges of the upright wall-sections.

In Figure 1 a wall section is indicated as a whole by the numeral 1, and this section, with its window opening W may form an entire side wall of a rectangular building structure, or other similar wall-sections may be added at the sides 40 and top of the illustrated section to form a larger wall in which the sections are properly bonded together.

This hollow, upright wall-section is fashioned with spaced outer walls 2 and 3 and an intermediate or interior partition 4 and as shown these walls and the partition provide spaced cells which may be left vacant, or, during the process of casting these cells may be filled with a sand core as indicated at S in Figure 11 and the core thereafter used as an interior filler, or this filler may be made up of heat-insulating material as an element in the section.

The whole wall-section is bounded by a transversely extending wall 5, as is also the window 55

opening **W**, and the bottom edge and the two side edges of section **1** are fashioned with extensions of these outer transverse walls that form outer spaced flanges **6** and **7** and an intermediate flange **8** that are alined with the face-walls **2** and **3** and the interior partition **4**.

As best seen in Figures 1 and 2 the top edge of the section **1** is fashioned with a single longitudinally extending edge-flange **9** that is alined with the flanges **6** of the section, and the plane top wall **5'** which is depressed below the top edge of the flange **9** is fashioned with angular recesses or notches **10**, shown as three in number to receive the ends of the ceiling or roof joists.

The interior structure of the section is reinforced by the use of wires **11** that are crossed to form the usual mesh, and in addition I employ cast metal tie bars **12** extending transversely of the section and fashioned with retaining heads **13** embedded in the face walls and the interior partition. As indicated in Figure 1 the ends of the wires **11** forming the reinforcing mesh are extended beyond the edges of the wall-section for use in making the bond between adjoining sections when the section is incorporated in a building structure.

In Figure 6, where the wall-section is shown supported on a concrete foundation **14** and its footing **15**, the latter is fashioned with longitudinally extending, spaced tongues **16** that form grooves to accommodate the flanges **6**, **7**, and the partition-flange **8** of the wall-section, and this joint is cemented together in suitable manner to form a seal, after the wall-section has been erected and placed in its true position on the footing or foundation.

In a one-room, one-story building structure, as for instance a garage, where the monolithic wall-section forms an entire side of the building, the angular upright walls **1** and **1a** in Figure 10 are joined by a corner bond **17** which is properly reinforced and cast of plastic concrete, and it will be seen that the two sets of three flanges of adjoining wall-sections provide grooves for the reception of tongues **18** that interlock with the flanges of the wall-sections. These bonds, which may be rounded at the corners as indicated may be cast in suitable molds erected at the corners of the building structure, and the bonded joint forms a fixed and permanent connection between the adjoining angular walls of the building.

At opposite sides of the building are erected two upright wall-sections **1**, **1** with the recesses or mortises **10**, **10**, **10** in their top edges, and these mortises or notches are adapted to receive the ends of cast concrete inverted T-joists or rafters **19** in Figure 13, that support the roof structure. After the rafters or joists have been placed in proper position and the side walls of the building structure are rigidly joined together at the corners, the roof, or ceiling as the case may be, is cast in place with three thicknesses or slabs as shown in Figure 13 with an inner slab **20**, an insulating layer **21**, and the roof covering or outer slab **22**. These slabs are built or cast upon the usual wire mesh that is supported on the shoulders of the inverted T-joists or supporters **19**, and they are fashioned in suitable and usual manner to complete the permanent weather-tight roof structure, for a single story building, as well as to form the ceiling and floor structure in a two (or more) story building.

For a finishing surface to the ceiling, horizontally disposed metal laths or strips **23** are supported between the joists, and a wire-mesh **24**

attached thereto is employed to bond the finishing coat of plaster, or the coats of plaster that may be applied in usual manner.

When a number of the wall-sections **1** and **1b** in Figures 7, 8 and 9 are incorporated in a building wall they are spaced apart a predetermined distance and their adjoining flanged edges are bonded together by cast concrete slabs **25**, **26**, and **27** in Figure 8 or a single solid pilaster **28** is used as in Figure 9.

In the form of Figure 8 the bonding slabs form spaced cells complementary to the cells of the adjoining wall-sections and these slabs **25**, **26**, **27**, that are cast in the molds or mold boxes **29** erected as in Figure 7 between the adjoining flanges of the wall-sections, form continuations of the inner and outer face-walls and of the intermediate partition of the wall-sections. The projecting ends **11** of the wire mesh are knotted as indicated and they are embedded within the spaced bonding slabs between the wall-sections. The mold-boxes **29** of course are removed after the bonding slabs have set.

The protruding wire ends **11** are also embedded in the solid pilaster-bond **28** in Figure 9, and this solid bond is fashioned with spaced tongues **30**, extending the full height of the pilaster, that are formed in the grooves between the flanges of the wall-sections, to insure a permanent bond or joint between the wall-sections.

In Figures 11 and 12 I have indicated a portion of a horizontally disposed mold box in which the wall-sections are cast "on the job", and the wall-sections are afterward erected to their upright positions. The mold box is made up of super-imposed, rectangular sections including the base **31** resting on the floor **F**, the two intermediate sections **32** and **33**, and the top section **34**. The two intermediate sections are provided with wall-tongues **35** extending around three sides of the rectangular box and spaced apart above the bottom of the mold and below the top of the mold to provide for the three edge-flanges of the wall section **1**, and another side of the mold box is provided at the inner side of its wall **45** with forms that fashion the mortises **10**, the plane top **5'** and the top tongue **9** of the wall sections.

The adjoining faces of the superimposed mold-box-sections are grooved at **36** and the crossed reinforcing wires **11** are laid in the successive sets of grooves to form the wire-mesh in each slab of the wall-section.

As a core for use in casting the successive slabs of the wall section **1** may use sand, as at **S** in Figure 11, and if desired this core may remain within the completed wall-section as a permanent filling. If the wall-section is to be hollow, as in Figure 3 for instance, this sand core may be blown out through holes provided for the purpose in the face-slabs or face-walls of the wall section, in well known manner. In some instances a heat-insulating material may be substituted for the sand-core as a permanent feature of the wall-section.

Having thus fully described my invention, what I claim as new and desire to secure by Letters Patent is:

1. A hollow monolithic wall-section comprising parallel spaced face walls and an intermediate partition, transverse edge-walls having spaced flanges forming extensions of the face-walls and partition, the top edge-wall having a single flange forming an extension of one of the face-walls, and said top edge wall having a number of open

front mortises closed at the rear by said last mentioned face wall for the support of joists or rafters.

2. A hollow monolithic wall-section comprising two spaced face walls and an intermediate partition, transverse edge-walls having spaced flanges forming extensions of the face-walls and partition, a reinforcing wire-mesh embedded in said

face-walls and partition and having ends projecting through the flanges, the top edge-wall having a single flange forming an extension of one of the face walls, and said top edge wall having a number of open-front mortises closed at their rear ends by said last mentioned face wall and located below said single flange. 5
